UNITED STATES PATENT OFFICE

EDWARD R. MARBACH, OF CLEVELAND, OHIO

YIELDING STOP

Application filed May 25, 1931. Serial No. 539,648.

This invention relates to a yielding stop, and especially to an adjustable stop adapted to yieldingly limit the movement of one member toward or away from another member, and is especially adapted to limit the outward movement of doors. While my invention is especially adaptable for use in connection with doors of motor vehicles and the like it is never the less well adapted for many other uses, hence I do not restrict myself to a stop for doors.

My improved stop is of the type comprising an arm, one end of which is pivotally attached to one member, such as a door frame, and slidably mounted in another member, such as the door itself. On its innermost end within the confines of the door is a resilient member, adapted to coact with the inner surface of the door, to limit its swinging movement and prevent damage to the hinges.

Such stops have been used in the past, however, but they have been difficult to assemble and have been so constructed as to require the handling of several independent parts, to position the stop on the door. Often the assembly of these parts was difficult and required considerable skill and time, thereby increasing the cost of the article on which they were used and making repairs difficult.

The general object of this invention is to provide an adjustable stop member which will yieldingly limit the movement of one member toward or away from another.

A more specific object is to provide a stop adapted to yieldingly limit the movement of one member to or from another member, which stop will be easily and economically manufactured, and so constructed as to comprise a minimum number of separate parts, enabling it to be readily secured in place with a minimum amount of time and labor.

Other objects of this invention will become apparent from the following description referring to the accompanying drawing, and the essential and novel characteristics will be set forth in the claims.

Referring to the accompanying drawing wherein I show a preferred embodiment of my invention;

Figures 1 and 2 are sectional views illustrating my improved stop in use;

Figure 3 is a side elevation of my improved stop, on an enlarged scale, certain portions thereof being broken away, to more clearly illustrate the internal construction;

Figure 4 is a horizontal section as indicated by the lines 4—4 on Figure 3;

Figure 5 is a vertical section as indicated by the lines 5—5 on Figure 3;

Figure 6 is a vertical section and is indicated by the lines 6—6 on Figure 4;

Figures 7 and 8 are perspective views illustrating certain parts of my improved stop;

Figure 9 is a diagrammatic view of the part shown in Figure 8;

Figure 10 is a perspective of a modified form of my improved stop.

Referring again to the drawing, my improved stop is generally indicated at 10, and is shown as used in conjunction with a hinged member such as the door 11. In Figures 1 and 2 a relatively stationary member or door frame is indicated at 12. Secured to the face 13 of this frame is a hinge member 14, to which is pivoted by means of a pivot pin 15 a complementary hinge member 16, which is, in turn, secured to the door 11.

My improved stop 10 comprises a rod or bar 20, one end of which is pivoted as at 21 to a bracket 22, in turn secured by suitable bolts or screws 23, to the door frame 12. The other end of the bar 20 passes through a restricted opening 25 in the edge of the member 11, and carries adjacent its innermost end 26 a resilient stop or bumper member 26.

The bracket 22 supports the stop member and is secured to the door frame 12 by suitable bolts or screws 23 as heretofore described. This bracket 22 preferably comprises a substantially flat plate 30, the ends of which are folded rearwardly and then inwardly to a position contacting with the center portion of the plate. Before the plate is bent suitable openings 31 and 31a are formed therein, and so located that when the plate is bent or formed the openings 31a overlie the openings 31. It will be noticed that the openings 31a are smaller than the openings 31 and the portion of the plate ad-

60

100

adjacent these openings 31a is bent rearwardly, forming a counter sunk opening, adapted to readily receive the screws 23, which when in place will lie flush with the surface of the bracket 22.

The plate 22 forms a socket or pivot to which the limit rod or bar 20 is pivoted. The rod 20 has on one end an enlargement 32 adapted to fit in a socket 33 formed between the rear and front portions of the plate or bracket 22. The bar 20 extends forwardly from the socket 33 through a slotted opening 34 in the front face of the plate 22. The rod 22 is preferably inserted in the opening 34 before the bracket is formed, and the bracket is thereafter placed in a suitable press, so arranged as to cause the bracket 22 to substantially encompass the enlarged portion 32 of the bar forming a socket therefor. The resilient stop 26 comprises a truncated cone preferably made of rubber or some similar resilient material, and is so constructed that it may be readily placed in position on the end of the bar 20, opposite the pivot 31 with a minimum amount of effort, and when placed in position thereon will be difficult to remove, thereby guarding against inadvertent displacement. Vulcanized within the cone is a metallic washer or cup 40, provided with a suitable opening 41 through which the rod 20 freely passes. Within the washer 40 is placed a spring 44, comprising a perforated disc 45 having a plurality of outwardly extending ears 46, adapted to extend beyond the outermost edge of the disc 40 and serve to space the retaining spring, a predetermined distance from the face 47 of the stop 26. This spring 45 is also provided with a plurality of tapered prongs 48, adapted to engage the serrations or indentations 35 on the bar 20.

In the form shown, there are four sets of serrations 35, and these sets are oppositely disposed in pairs, and would form, if the serrations were continuous, a substantially continuous thread. However I find it advantageous for reasons hereinafter explained to interrupt this thread.

The construction of the spring member 45 is such that when it is desired to assemble the stop 26 and rod 20, it is only necessary to slide the rod through the enlarged opening 36 in the stop. The edges 50 of the prongs 48 of the spring member 45 will then contact with the face of the rod and engage the indentations or serrations 35. As the prongs 48 are inclined outwardly from the plate or spring 45, they will readily pass over the serrations 35 when the stop is drawn onto the rod 20, and will act to restrain the stop against movement from the rod.

When an attempt is made to withdraw the stop from the rod by merely pulling or sliding it from the rod, the edges 50 of the prongs 48 of the spring member 45 will en-

gage the serrations 35 of the rod and the pulling movement will tend to bend the ends 50 of these ears inwardly thereby gripping the rod tighter and coacting with the serrations 35 to prevent the removal of the stop 26 by such pulling movement. Hence the adequate protection is had against inadvertent displacement by any such movement.

The construction is such that the stop 26 may be removed for replacement. Reference will now be had to the diagrammatical illustration in Figure 9, which illustrates the development of the various ears 46 and prongs 48 of the spring 45. It will be noted from Figure 9 that the prongs 48 are tapered so that they extend varied distances from the face of the disc 44. The prong 48a extending outward the greatest distance and the prong 48b extending slightly less, the prong 48c a like amount less than the prong 48b, and the prong 48d extends substantially the same distance as the prong 48b. This forms a simulated thread, hence when the stop 26 is rotated the prongs 48 will rotate on the serrations 35 in the same manner as a nut on a bolt and the stop 26 may be thus withdrawn from the rod 20.

As heretofore mentioned the serrations 35 do not form a continuous thread. They are interrupted by high portions 55, hence when the stop 26 is rotated the prongs 48 will encounter these high portions 55, likewise the base 56 of the serrations, is flat conforming to the flattened face 50 of the prongs 48, thereby insuring against inadvertent displacement by rotation of the stop 26, but at the same time permitting the stop 26 to be readily removed when it is desired to replace the same.

In Figure 10 I illustrate a modified form of my device. In this figure the bar 20 and the stop 26 are constructed in the same manner as heretofore described. The bracket however comprises an L-shaped plate 60, the outer edges of each arm of the L being bent rearwardly and then outwardly along the inner face of such arms. Suitable openings 31a are provided in each arm of the L to enable the member or bracket 60 to be readily secured to two adjacent surfaces of the door frame.

From the foregoing description it will be apparent that I have provided an improved stop which comprises a minimum amount of parts, namely two, the rod assembly and the stop assembly which are readily positioned on a door or similar article, and are so constructed as to prevent inadvertent displacement and yet permit adjustment and replacement to be made readily.

Having set forth the principles of my invention, and described and illustrated an embodiment thereof for practical use, what I claim and desire to secure by Letters Patent, is,

1. A stop comprising a rubber composition

member having an axial opening for receiving a serrated bar therethrough spring means comprising a pair of metallic discs arranged in contact, one disc of the pair having a plurality of prongs bent outwardly and away from the other disc, vulcanized in the rubber member and adapted to engage the serrations of the bar to prevent inadvertent movement between the rubber member and the bar.

2. A resilient composition stop member having inserted therein a metallic disc provided with an aperture through which an indented rod may be freely passed a second disc substantially in contact with the first named disc and having a plurality of prongs bent outwardly from the face thereof extending away from the first named disc, wherein said composition completely fills the space between the first named disc and the prongs of the second named disc.

3. A rubber bumper provided with an aperture whereby it may be slid onto a serrated rod, a flanged apertured disc vulcanized in said bumper and through which the rod may pass, a second disc arranged to contact with the first named disc and having a plurality of series of ears, one of said series arranged to be embraced by the flange of the first named disc and the other series projecting outwardly from the first named disc and arranged to engage the serrations on the rod, whereby when the bumper is shoved onto the rod the rubber will permit the ears to spring past said apertures, but when the bumper is drawn in the opposite direction the rubber between the ears and the other disc will be compressed and aid the ears in preventing the withdrawal of the bumper.
